DESIGN FOR A HAT

Zinaida Harpignies, Kew Gardens, N. Y.

Application October 7, 1942, Serial No. 108,454

Term of patent 3½ years

To all whom it may concern:

Be it known that I, Zinaida Harpignies, a citizen of Belgium, residing at 84-09 Talbot Street, Kew Gardens, Long Island, in the county of Queens and State of New York, have invented a new, original, and ornamental Design for a Hat, of which the following is a specification, reference being had to the accompanying drawing, forming part thereof.

In the drawing:

Fig. 1 is a plan view of a hat showing my new design, in open position,

Fig. 2 is a side perspective view of the hat shown in Fig. 1 as when worn, and

Fig. 3 is a bottom perspective view of the hat shown in Fig. 2.

I claim:

The ornamental design for a hat, as shown.

ZINAIDA HARPIGNIES.
